UNITED STATES PATENT OFFICE

EDWARD H. BELDEN, OF TOLEDO, OHIO, ASSIGNOR TO THE WILLYS-OVERLAND COMPANY, OF TOLEDO, OHIO, A CORPORATION OF OHIO

FLEXIBLE ENGINE SUPPORT

Application filed September 5, 1922. Serial No. 586,135.

This invention relates to automotive vehicles, and more particularly to the manner of supporting or connecting the driving motor to the vehicle frame.

3 An object of the invention is to provide a connection between the vehicle frame and the motor which, while effective to support the motor with the necessary firmness or rigidity, is at the same time sufficiently yielding to absorb motor vibrations and thus materially reduce the amount of vibration transmitted to the vehicle frame and body. Other objects will appear from the detailed description to follow:

15 Referring to the drawing forming a part hereof:

Figure I is a top plan view of a portion of an automotive vehicle frame and motor supported thereby;

20 Fig. II is a detail sectional view drawn to a larger scale, taken on the line II-II of Figs. I and III;

Fig. III is a side view of the support shown in Fig. II with the engine foot removed;

25 Fig. IV is a cross sectional view taken on the line IV-IV of Fig. I; and

Fig. V is a perspective view of the attaching bracket shown in Fig. IV.

The same reference numbers refer to the 30 similar parts throughout the views.

Two channels 5, connected by cross braces 6 and 7 comprising the forward end of the vehicle frame, support the driving motor or engine 8 by a connection at each of its four corners. As is common in such frame structures the side frame channels are of varying depth, being tapered toward the front end of the frame, thus the channel section appearing in Fig. IV is narrower than that 35 in Fig. II. Each of the four corners of the engine is provided with a supporting foot the two forward corners each having a foot 10 while the two rear corners each have a foot 11.

40 Referring first to Figs. II and III which illustrate the structure for connecting the rear corners of the engine to the frame, a bracket 12, riveted at 13 to the inner face of the channel, is shown secured by a pair of bolts 14 to two disks 15. The two bolts 14

are positioned diametrically opposite each other and each has one or more spacing washers 16 interposed between the bracket 12 and the adjacent fabric disk. A thin spacing washer, not shown, is also preferably employed between the two disks at these bolts. A plate or bracket 19 is secured to the two fabric disks 15 by bolts 20 also positioned at diametrically opposite points, but spaced 90 degrees from the bolts 14. These bolts carry 55 spacing washers 21, one of which separates the two disks while the other separates the plate 19 from the adjacent disk. The disks 15 may be constructed of a variety of materials, the essential feature being that the disks 60 in addition to having the necessary strength shall have the desired yielding, resilient and shock absorbing properties. An effective material for this purpose has been found to be a rubberized fabric; each disk being built 65 up of a number of layers with the warp and woof of each layer angularly displaced with reference to the warp and woof of the other layers. While two disks are shown in the drawing it will be evident that a greater 70 number may be employed if desired or even a single disk may be used. The plate 19 has a projection 23 on the side opposite the fiber disks which provides a seat for the foot 11 of the engine and a bolt 24 serves to firmly 75 secure those two members together.

The connecting structure for the two front corners of the engine differs from that described principally in the shape of the bracket and plate and in the fact that the plate is 80 attached to the pair of disks at the same side as the bracket. The bracket 26 which is riveted to the channels 5 at 27 is shown in Figs. IV and V. This bracket engages the channel 85 at that point, mentioned above, where the channel tapers in depth and the bracket is so bent that the projecting portion 28 is not parallel with the top edge but conforms to the slope of the lower flange of the channel. The prongs 30 and 31 are accordingly made 90 of unequal length the former being longer than the latter. The ends of these prongs 30 and 31 are secured by bolts 32 at diametrically opposite points to a pair of disks 33 95 similar in every way to the disks 15. A plate 100

35 is secured to the same disks by bolts 36 also arranged at diametrically opposite points and spaced 90 degrees from the bolts 32. Spacing washers 37 are also provided between the disks and between the bracket and prongs and the adjacent disk. The upper end of the bracket 35 constitutes a bolt 38 by which the bracket is secured to the engine foot 10.

10 It will be noted from an inspection of Fig. II that the upper bolt 20 and nut thereon project into an alining aperture in the bracket 12. This arrangement permits the bracket being brought closer to the disks than it 15 otherwise would and, what is more important, provides a safety support for the engine should the disks 15 for any reason fail. In the case of the forward support, the part 28 of the bracket 26 projects inward beneath 20 the engine foot 10 a sufficient distance to provide a safety support for that end of the engine should the disks 33 fail.

An engine mounting such as described while providing the necessary rigidity is at 25 the same time sufficiently flexible and yielding to absorb vibrations which otherwise would be transmitted to the frame and body of the vehicle.

While I have shown and described in detail a particular structural embodiment as 30 illustrative of my invention, I do not wish to be limited thereby, since various changes might be made therein without departing from the scope of the invention covered by 35 the appended claim.

Having thus described my invention, what I claim as new and desire to secure by Letters Patent, is:

In combination, a vehicle frame, an engine frame, a vertically extended bracket connected to one of the frames, a bifurcated bracket secured to the other frame and cooperatively disposed parallel to and adjoining the first mentioned bracket on either side, 45 and a nonmetallic vibration dampening member secured to each of the brackets and interconnecting the same.

In testimony whereof, I affix my signature.

EDWARD H. BELDEN.
